No. 884,772.

PATENTED, APR. 14, 1908.

C. M. SORENSEN,

CLAMP.

APPLICATION FILED JUNE 13, 1907.

UNITED STATES PATENT OFFICE.

CHARLES M. SORENSEN, OF GREENPOINT, NEW YORK.

CLAMP.

No. 884,772.

Specification of Letters Patent. Patented April 14, 1908.

Application filed June 13, 1907. Serial No. 378,716.

To all whom it may concern.

Be it known that I, CHARLES M. SORENSEN, a citizen of the United States, and a resident of Greenpoint, in the county of Kings and State of New York, have made and invented certain new and useful Improvements in Clamps, of which the following is a specification.

My invention relates to an improvement 10 in clamps, designed for any of the various purposes and uses for which small clamps are ordinarily employed. In devices of this kind, as ordinarily constructed, there are usually employed two or more clamping 15 screws, and two or more movable clamping members, one of which is designed to secure the device or article to a table, bench or other suitable support, and the other for clamping, holding or securing the article to 20 be held in place to the body or frame of the clamp, thereby necessitating several adjustments and rendering the article a comparatively expensive one, in view of the number of parts going to make up the same.

25 The object of my invention is to so construct the clamp that several of the movable parts heretofore considered necessary, may be omitted, thereby materially reducing the cost of the same and enhancing the neat and 30 finished appearance thereof, the several parts being so constructed and arranged that the one clamping member will suffice to not only bind or securely hold the article to the table or other support, but also operate to bind or 35 hold the rod, pipe, tube or other article in its proper position therein, the clamp consisting of but two parts and a binding or set crews. With these and other ends in view, the invention 40 consists in certain novel features of construction and combinations of parts, as will be hereinafter fully described and pointed out in the claims.

45 In the accompanying drawings, Figure 1 is a perspective view of my improved clamp, showing the same in its operative position. Fig. 2 is a plan view. Fig. 3 is a sectional view taken on the line 3—3 of Fig. 2. Fig. 4 is a sectional view taken on the line 4—4 of Fig. 3, and Fig. 5 is a detached perspective 50 view of the clamping member. Fig. 6 is a view similar to Fig. 1 showing a modified form of my clamp, and Fig. 7 is a view similar to Fig. 5 showing the construction of the clamping member in its modified form.

55 Referring to the drawings, the body por-

tion of the clamp, which is preferably made of metal, is shown as consisting of two parts rigidly secured together, the lower part 1 being U-shaped as shown in the drawings, and having a threaded opening 2 extending through its rear wall, adapted to receive the set screw 3, and recesses 4 formed in the ends of its forwardly extending arms 15 for the purpose hereinafter set forth. The upper part 5 of the body portion is also U-shaped, 60 the forwardly extending arms 16 thereof being considerably longer than the arms 15 of the lower part 1, and having downwardly extending end portion or portions 6 at their outer extremities, as clearly shown in Figs. 70 1 and 3.

While I have shown the body portion as being made of two parts rigidly secured together by means of the screws 17, it will of course be understood that I may make it of 75 one piece without in any way departing from the spirit of my invention. It will be also understood without further description or illustration that the downwardly extending ends 6 which assist in holding the article to 80 its support, may be scored, corrugated or otherwise roughened to assist in holding it in place, or on the other hand, may have applied thereto a lining of fabric to avoid injury to said support.

85 The movable clamping member 7 is provided with a vertical central portion 8, adapted to fit snugly between the arms of the body portion of the clamp with which it has sliding contact, and with horizontal guide 90 lugs or flanges 9 on each side thereof, which are adapted to fit and slide within the recesses 4 formed in the arms 15 of the lower part 1 of the body portion, as shown in Fig. 1, in order that the clamping member may be 95 movably secured thereto. The clamping member is further provided with a plate 10, the upper edge of which is adapted to bear against the lower surfaces of the arms 16 of the body portion. The central portion 8 is 100 provided with a vertical recess 11 adapted to receive the rod, tube, standard, or similar device which is to be clamped in position.

Having described the construction of my device, I will now explain the manner of 105 using the same: The clamp is placed in position upon the table, shelf or other suitable support 12, with its bent ends 6 lying against one side thereof, and the clamping plate 10 of the clamping member 7 lying upon the op- 110

posite side, the rod, tube, standard, or other similar device being inserted in the opening or socket 14, formed between the recessed vertical portion 8, and the inner surface of the body portion of the clamp, as clearly shown in Figs. 1 to 4. By now rotating the set screw 3, it will force the rod or similar device 13 into the recess 11, and at the same time, owing to the pressure which the screw 10 exerts upon the rod 13, the clamping member 7 will be forced thereby against the adjacent side of the support 12; whereby the clamp will be firmly secured to said support and at the same time and by the same operation, 15 the rod 13 or similar device, will be firmly gripped between the set screw and the clamping member 7.

In Figs. 6 and 7 I have shown a modified form in which the rod, tube, standard, or other similar device may be held in either a vertical or a horizontal position as may be desired. As shown in Fig. 6, the body portion of the clamp is practically the same as that shown in Fig. 1, the only essential difference being in the construction of the recesses 19 in the forwardly extending arms of the body portion, which recesses are made wider and deeper than the corresponding recesses 4, shown in Fig. 1, and are curved at the 20 inner ends, as shown. The clamping member shown in Fig. 7 is similar to the one shown in Fig. 5, the essential difference residing in the construction of the horizontal guide lugs or flanges 20, which are made 25 wider than the corresponding members shown in Fig. 5, and are provided with horizontal recesses 21, adapted to receive the rod, tube, standard, or similar device which is to be clamped in position. The body portion and 30 clamping member are assembled, held in position, and secured to the support in a manner similar to that described with respect to 35 Figs. 1 to 5, inclusive.

It will be understood from the above description that the rod or similar device may be held in a vertical position, as shown in full lines in Fig. 6, or, if desired, it may be held in a horizontal position as shown in dotted lines in said figure.

I have shown a piece of felt or other similar material 18, secured to the face of the clamping plate to avoid injury to the support, though it will of course be understood that I may leave the face of the plate exposed as shown in Figs. 1 to 5, inclusive, if I so desire.

It will thus be seen that I have provided an efficient clamp, by means of which a rod, tube, standard, or similar device may be secured therein, and said clamp secured to a support by one and the same operation. It will also be seen that the clamp is adapted to be used with rods or similar devices of various sizes, and is capable of being attached to 65 supports of different thicknesses.

Having fully described my invention, what I claim as new and desire to secure by Letters Patent, is:—

1. A clamp comprising a U-shaped body having a downwardly extending end to assist 70 in holding said body to a support, a single movable clamping member engaging with said body, and means for simultaneously clamping said body to a support and an article in said body, substantially as described. 75

2. A clamp comprising a body provided with forwardly extending arms, support engaging means extending at an angle from the ends of said arms, a single movable clamp 80 engaging with said body, and means for simultaneously clamping said body to a support and an article in said body, substantially as described.

3. A clamp comprising a body provided with forwardly extending arms, support engaging means extending at an angle from the ends of said arms, a single movable clamping member engaging with said body, and a clamping screw threaded in said body for simultaneously clamping said body to a support 85 and an article in said body, substantially as described.

4. A clamp comprising a body provided with a bent end to assist in holding said body to a support, recesses formed in said body, a clamping plate provided with guide lugs engaging said recesses, and means for simultaneously clamping said body to a support 95 and an article in said body, substantially as described.

5. A clamp comprising a body with a bent clamping end whereby to assist in securing said body to a support, recesses formed in said body, a clamping plate provided with guide lugs engaging in said recesses, and a screw 105 passing through said body whereby to simultaneously clamp said body to a support and an article in said body, substantially as described.

6. A clamp comprising a body provided 110 with arms having bent ends to assist in holding said body to a support, recesses formed in said body, a movable clamping plate provided with guide lugs fitting in said recesses, and a screw extending through said body 115 whereby to simultaneously secure said body to a support and an article in said body, substantially as described.

7. A clamp comprising a U-shaped body having its end bent downwardly to assist in 120 clamping said body to a support, recesses formed in said body, a single grooved clamping plate provided with guide lugs fitting in said recesses, and a set screw whereby to simultaneously clamp said body to a support 125 and an article between said clamping plate and body, substantially as described.

8. A clamp comprising a U-shaped lower body portion provided with recesses, an upper U-shaped body portion rigidly secured to 130

said lower body portion and provided with bent ends for assisting in clamping said body to a support, a single recessed clamping plate provided with guide lugs fitting in said recesses in the lower body portion, and a screw for moving said plate and simultaneously clamping said body to a support and an article between said body portion and clamping plate, substantially as described.

10 9. A clamp comprising a body provided with arms having bent ends to assist in holding said body to a support, a movable clamping plate provided with guide lugs formed with vertical and horizontal recesses, and a screw extending through said body whereby to simultaneously secure said body to a support and an article in one of the recesses formed in said clamping plate, substantially as described.

10. A clamp for supporting a rod or other article, comprising a body provided with a clamping end and formed with recesses therein, a movable clamp provided with guide lugs fitting in said recesses formed in said body and provided with vertical and horizontal grooves, whereby to secure an article in horizontal or vertical position, and a screw extending through said body whereby to simultaneously secure the latter to a support and an article to said body; substantially as described.

Signed at New York, borough of Manhattan, in the county of New York, and State of New York, this 11th day of June, A.D. 1907.

CHARLES M. SORENSEN.
